(57) **CLAIM**

The ornamental design for a Christmas tree stand, as shown and described.

DESCRIPTION

FIG. 1 is a perspective view of a Christmas tree stand showing my new design with the support legs extended.

FIG. 2 is a top plan view of the design of FIG. 1 with the support legs retracted.

FIG. 3 is a bottom plan view of FIG. 2 with the support legs retracted; and,

FIG. 4 is a side view of the Christmas tree stand of FIG. 2, with all four sides being identical.

1 Claim, 4 Drawing Sheets**FIG. 1**

FIG. 2

FIG. 3

FIG. 4
